SPOOL

Louis E. Nykamp, Grand Rapids, Mich., assignor
to Grand Rapids Fibre Cord Company, Grand
Rapids, Mich.

Application April 18, 1938, Serial No. 202,638

7 Claims. (Cl. 242—119)

This invention relates to reels or spools to be used for the storage and shipment of cords. It has for its objects:

- 5 First, to provide a new and improved reel.
5 Second, to provide such a reel made primarily of paperboard or the like.
Third, to provide such a reel which is of rigid construction.
Fourth, to provide such a reel with suitable 10 bearings which permit the mounting of the reel on an axle or spindle, either of the machine employed in making the cord to be wound thereon, or to permit the reel to serve as the supply reel on the machine employing the cord.
15 Other objects and advantages pertaining to details and economies of construction and operation will appear from the description to follow. The invention is pointed out in the claims. A preferred embodiment of my invention is illustrated 20 in the accompanying drawing, in which:

Fig. 1 is a perspective view of my improved reel.
Fig. 2 is an end elevational view of the reel.

Fig. 3 is a detail sectional view taken on the line 3—3 of Fig. 1, drawn to a larger scale than in Fig. 1.

Fig. 4 is a detail sectional view taken on line 4—4 of Figs. 1 and 3.

Fig. 5 is a perspective view of the plate forming the bearing for the reel.

50 Fig. 6 is a view showing certain of the parts in disassembled relationship.

Referring to the drawing, the reel is shown with heads 1 and a barrel 2. The heads 1 are preferably paperboard disks and each head is provided with a centrally disposed square aperture 3. The barrel 2 is made up of plates 4 of sheet metal. These plates are preferably square and are disposed parallel to the head 1 when they are in place. The plates have central bearing apertures 5 and ears 6 extending from their ends.

An inner core 7 is made up by wrapping a sheet 8 of cardboard around the plates 4. The edges of the sheet of cardboard overlap as shown in Fig. 3 and staples 9 hold the cardboard in position. Apertures 10 in the cardboard sheet 8 receive the ears 6 of the plates 4 and tend to hold the plates in the desired position.

The inner core 7 fits within and extends through the central aperture 3 of the head 1. Flaps 11 extend from the end edges of the core 7 and lie along the outer surface of the head 1. Staples 12 passing through the head and the flaps hold them in position.

An outer cylindrical core 13, preferably of paper, fits around the inner core 7, touching at

the corners of the inner core as shown in Fig. 3. The inner core thus serves to support and position the outer core and the outer core 13 is fitted between the heads 1 and serves as a spacer and bracing member for holding them in position.

It will be apparent that this arrangement provides an extremely rigid, light weight reel of cardboard. The inner core with its flaps tends to hold the head 1 in place and the outer core 13 serves to brace the heads and to serve as a barrel for receiving the cord wound on the spool. The plates 4 with their bearing apertures 5 make it possible for a shaft to be properly held and centered to permit the reel to be used either as a supply reel on a machine using the cord or as a reel to receive cord from the machine making it.

The reel may be easily and simply assembled from inexpensive cardboard such as strawboard and may be put together by the simple use of wire staples which are in common use in the box making art.

Having thus described my invention, what I claim as new and desire to secure by Letters Patent is:

1. In a reel, the combination of a pair of cardboard heads with central square apertures, a barrel made up of a pair of square sheet metal plates disposed parallel to said heads and centrally apertured to form bearings and having ears projecting from their edges and an inner core of square cross section formed of cardboard wrapped to overlapping relation around said plates and stapled and apertured to receive said ears to hold said plates in position, said inner core being fitted in the apertures of said heads and having flaps extending from the end edges thereof and lying on the outer faces of said heads and stapled thereto, and an outer cylindrical core fitted around and supported by said inner core and fitted between and bracing said heads.

2. In a reel, the combination of a pair of cardboard heads with central polygonal apertures, a barrel made up of a pair of polygonal sheet metal plates disposed parallel to said heads and centrally apertured to form bearings and having ears projecting from their edges, and an inner core of polygonal cross section formed of cardboard wrapped around said plates and stapled and apertured to receive said ears to hold said plates in position, said inner core being fitted in the apertures of said heads and having flaps extending from the end edges thereof and lying on the outer faces of said heads and stapled thereto, and an outer cylindrical core fitted around and

supported by said inner core and fitted between and bracing said heads.

3. In a reel, the combination of a pair of cardboard heads with square apertures, a barrel made up of a pair of square sheet metal plates disposed parallel to said heads and centrally apertured to form bearings and having ears projecting from their edges, and an inner core of square cross section formed of cardboard wrapped around said plates and apertured to receive said ears to hold said plates in position, said inner core being fitted in the apertures of said heads and having flaps extending from the end edges thereof and lying on the outer faces of said heads, and an outer cylindrical core fitted around and supported by said inner core and fitted between and bracing said heads.

4. In a reel, the combination of a pair of cardboard heads with central polygonal apertures, a barrel made up of a pair of polygonal sheet metal plates disposed parallel to said heads and centrally apertured to form bearings and having ears projecting from their edges and an inner core of polygonal cross section formed of cardboard wrapped around said plates and apertured to receive said ears to hold said plates in position, said inner core being fitted in the apertures of said heads and having flaps extending from the end edges thereof and lying on the outer faces of said heads, and an outer cylindrical core fitted around and supported by said inner core and fitted between and bracing said heads.

5. In a reel, the combination of a pair of heads with central polygonal apertures, a barrel made up of a pair of polygonal plates disposed parallel to said heads and centrally apertured to form

bearings and having ears projecting from their edges, and an inner core of polygonal cross section formed of sheet material wrapped around said plates and apertured to receive said ears to hold said plates in position, said inner core being fitted in the apertures of said heads and having flaps extending from the end edges thereof and lying on the outer faces of said heads, and an outer core fitted around and supported by said inner core and fitted between and bracing said heads.

6. In a reel, the combination of a pair of heads, a barrel made up of a pair of polygonal plates disposed parallel to said heads and centrally apertured to form bearings and having ears projecting from their edges, and an inner core of polygonal cross section of sheet material wrapped around said plates and apertured to receive said ears to hold said plates in position, said inner core being fastened to said heads at its ends, and an outer core fitted around and supported by said inner core and fitted between and bracing said heads.

7. In a reel, the combination of a pair of heads, a barrel made up of a pair of plates disposed parallel to said heads and centrally apertured to form bearings and having ears projecting from their edges, and an inner core of sheet material wrapped around said plates and apertured to receive said ears to hold said plates in position, said inner core being fastened to said heads at its ends, and an outer core fitted around and supported by said inner core and fitted between and bracing said heads.
